US0D1067914S

(12) **United States Design Patent** (10) **Patent No.:** **US D1,067,914 S**
(45) **Date of Patent:** **** Mar. 25, 2025**

(54) **OPTICAL SCANNER HANDLE**

(71) Applicant: **Hand Held Products, Inc.**, Charlotte, NC (US)

(72) Inventors: **Dean J. Bidwell**, Renton, WA (US); **David K. Memke**, Bainbridge Island, WA (US); **Michael James Wells**, Lake Forest Park, WA (US); **Tim Zurmoehle**, Seattle, WA (US); **William Herweh, III**, Seattle, WA (US); **Churu Yun**, Seattle, WA (US); **Mark Oberpriller**, Peachtree Corners, GA (US); **Matthew McElvogue**, Seattle, WA (US); **Rajat Shail**, Chicago, IL (US); **John S. Bandringa**, Everett, WA (US); **Roger Jackson**, Lake Forest Park, WA (US)

(73) Assignee: **HAND HELD PRODUCTS, INC.**, Charlotte, NC (US)

(**) Term: **15 Years**

(21) Appl. No.: **29/772,489**

(22) Filed: **Mar. 2, 2021**

Related U.S. Application Data

(63) Continuation of application No. 29/759,409, filed on Nov. 23, 2020, now Pat. No. Des. 917,487, which is (Continued)

(57) **CLAIM**

The ornamental design for an optical scanner handle as shown and described.

DESCRIPTION

FIG. 1 is a top right perspective view of an optical scanner handle in accordance with the present invention;

FIG. 2 is a front view of the optical scanner handle of FIG. 1;

FIG. 3 is a rear view of the optical scanner handle of FIG. 1;

FIG. 4 is a left side view of the optical scanner handle of FIG. 1;

FIG. 5 is a right-side view of the optical scanner handle of FIG. 1;

FIG. 6 is a top view of the optical scanner handle of FIG. 1; and,

FIG. 7 is a bottom view of the optical scanner handle of FIG. 1.

1 Claim, 7 Drawing Sheets

Related U.S. Application Data

a continuation of application No. 29/663,671, filed on Sep. 18, 2018, now Pat. No. Des. 907,634, which is a continuation of application No. 29/572,907, filed on Aug. 1, 2016, now Pat. No. Des. 829,212.
